GAS FIRED RADIANT TUBE BURNER

Melvin J. Parker, Garden City, and Alexander J. Turpin, Stewart Manor, N. Y., assignors to Hauck Manufacturing Co., Brooklyn, N. Y., a corporation of New York

Application January 16, 1956, Serial No. 559,217

18 Claims. (Cl. 126—91)

This invention relates to gas burners, particularly for firing into a tube.

Such a tube may be made of a special high temperature alloy and operate at red heat, the tube then being used for radiant heating. In other cases the burner may fire into an immersion tube, and in still others it may fire into a finned tube for convection heating.

The radiant tube is the most common in use, compared to immersion or convection tubes. In the present specification these tubes, whether radiant, immersion or convection, will be referred to generically as "heater tubes," for although heated by the burner flame, they are themselves used to heat something else.

The heater tube may be straight, or reversely bent to U shape, or doubly reversely bent to W shape or curved to O shape, etc. In all cases the burner is disposed in one end of the tube, and hot gases are discharged at the other end, and ordinarily the ends will pass through and be supported by appropriate masonry. The primary object of the present invention is to generally improve gas burners for such "tube firing."

For tube firing the burner should produce an elongated slender flame, and one primary object of the present invention is to provide a gas burner which will produce such a flame. A further object is to provide means for controlling or adjusting the flame length over a very wide range. We have found that this may be done by using either, and preferably both, of two features. One feature is the use of a spinner or deflecting vane for whirling the air supply as it is admitted to the annular region between the gas tube and the heater tube. In tube firing the whirled air produces a lengthened flame. By making the deflecting vane angularly adjustable, and by providing a control lever and a dial and scale, the deflecting vane may be used to help control the flame length.

In accordance with another feature and object of the invention, a part of the air supply is admitted through ports into the gas tube, and the amount is controlled by a sleeve which is axially slidable on the gas tube. A part of the sleeve is preferably shaped to act as a valve for the air supplied outside the gas tube, and the arrangement is preferably such that movement of the sleeve in one direction reduces the air supply into the tube (the primary air) and increases the air supply around the tube (the secondary air), while movement in the other direction increases the primary air and decreases the secondary air. The former provides a long luminous flame while the latter provides a short sharp blue flame. This adjustment may be made from outside the burner, and thus helps provide the very wide range of adjustment previously mentioned.

To accomplish the foregoing general objects, and other more specific objects which will hereinafter appear, our invention resides in the gas burner elements, and their relation one to another and to the heater tube, as are hereinafter more particularly described in the following specification. The specification is accompanied by drawings, in which:

Fig. 1 is a partially sectioned longitudinal view of a gas burner embodying features of our invention;

Fig. 2 is a schematic view showing the burner applied to a U tube;

Fig. 3 is a fragmentary longitudinal section at the gas burner tip and flame retention nozzle;

Fig. 4 is an end view of the burner looking in the direction of the arrows 4—4 in Fig. 1;

Fig. 5 is a similar view, but partly sectioned approximately in the plane of the line 5—5 in Fig. 1; and

Fig. 6 is a transverse section taken approximately in the plane of the line 6—6 of Fig. 1.

Referring to the drawing, and more particularly to Fig. 2, we there show a heater tube 12 of the reversely bent or U type. This may be made of a heat resistant alloy steel for operation as a radiant heater. The entrant end

14 of the tube passes through a suitable masonry or firebrick or like heat resistant wall 16. The discharge end 18 of the tube leads to a suitable flue, here indicated at 20. The rear end of the burner is generally designated B, and it is secured to the entrant end 14 of heater tube 12,

20 as by means of a plate 22 which is welded to the end of tube 14, and bolts which secure a flange 24 of the "air body" 26 to the plate 22. Air is supplied through pipe 28 and may be controlled by a valve 30. Gas is supplied through a pipe 32 and may be controlled by a valve 34.

25 The gas line is connected to a "gas body" 36 which is secured to the air body 26. High voltage electricity for ignition purposes may be supplied at an insulated terminal 38.

The air may be supplied at a pressure of, say, 4 to 32 30 oz. per square inch. The gas may be supplied at a pressure of, say, 2 to 32 oz. per square inch. The valve 30 may be used to regulate the total amount of air (primary and secondary), or in the case of a bank of burners, there may be a single automatic control valve which controls 35 an entire bank of burners. The total air is determined by the need for complete combustion.

The showing in Fig. 2 is schematic rather than practical, for with vertical supply pipes, as shown, the heater tube would commonly be disposed in a horizontal plane with 40 both legs of equal length. With the U disposed in a vertical plane, as shown, the supply pipes would ordinarily run horizontally. Accordingly, in Fig. 2 the projection of the burner leg of the heater tube at 14 is exaggerated, and would ordinarily be a matter of only a few inches from the fire wall. The heater tube may have additional 45 passes, and thus be W in shape instead of U in shape, and, on the other hand, may have a single pass, entering a furnace at one side and leaving on the other.

The burner may be described with reference first to 50 Fig. 1 of the drawing. It comprises a tube 40 which receives gas or a mixture of gas and primary air. A gas which is high in hydrogen, as in the case of most artificial gases, will require little or no primary air. A gas which is low in hydrogen, typically propane, butane, or 55 natural gas, will require more primarily air if ignition is to be maintained. Of course, the total amount of air, primary and secondary, is fixed for a given rate of fuel consumption, in order to maintain complete combustion.

The tube 40 may be called a gas tube. It terminates 60 at its inner end in a burner tip 42, and the construction of this is better shown in Fig. 3. The air supply body 44 (Fig. 1) which surrounds the rear end of the tube 40 supplies primary air through a series of ports 46 in tube 40 and supplies secondary air through an annular passage 48 around the tube 40 so that the secondary air flows 65 between the tube 40 and the main heater tube 14. The ports 46 are shown rectangular, but may have other shapes. The burner terminates in a flame retention nozzle 50 which has a diameter larger than the tube 40 and smaller than the heater tube 14. The flame retention 70 nozzle 50 is preferably nearly closed at its rear end by a plate 56, which surrounds the burner tip 42, but which

is radially spaced therefrom to provide an annular passage 58 around the tip for the flow of a portion of the secondary air.

There is an externally controlled means 52 to vary the gas-to-air ratio in the primary tube 40, and this preferably functions to simultaneously oppositely vary the primary and secondary air supplies. To accomplish this there is a sleeve 60 which surrounds the tube 40 and which is axially movable over the air ports 46, and the part 52 controls the position of the sleeve 60, in this case by means of a cross rod 62 passing through a positioning screw 64 the end of which is threadedly received in a matingly threaded bushing 66 which acts as a nut, and the outer end of which may be shaped with flats like a nut, as shown at 52. The bushing is held against outward movement by a screw 68, and against inward movement by head 52. The adjustment may be locked, as by means of a set screw 69, shown in Fig. 4. Screw 68 is too short to tighten against the bushing, and acts only to prevent axial movement. Screw 69 is long enough to act as a set screw to prevent rotation of the bushing.

The forward part of sleeve 60 is preferably shaped to act as a valve for the annular passage 48. It will thus be seen from inspection of Fig. 1 that movement of the sleeve toward the left reduces the primary air supply into the tube 40 and increases the secondary air supply around the tube 40, and, conversely, movement of the sleeve 60 toward the right increases the primary air supply and decreases the secondary air supply. Movement to the left increases the flame length and produces a long luminous flame. Movement to the right decreases the flame length and produces a short sharp bluish flame.

As was previously pointed out, the requirement of primary air depends on the nature of the gas being burned. Any subsequent axial adjustment of the sleeve 60 to control the flame length is relative to the sleeve position determined by the nature of the gas. Differently expressed, the axial adjustment is relative to some mean position, and that mean position depends on the particular gas being burned. Of course, the total amount of air is fixed by the requirement for complete combustion, and therefore the adjustment of the sleeve for flame length control is essentially an adjustment of the ratio of primary and secondary air. If the adjustments happen to change the total amount of air it is then necessary to readjust the main air valve 30 (Fig. 2) in order to maintain proper total air supply for complete combustion.

From inspection of Fig. 1 it will be seen that the flame retention nozzle 50 has a diameter substantially larger than that of the tube 40 but substantially smaller than that of the heater tube 14. It is concentrically spaced within the heater tube, as by means of three spacers 70 best shown in Fig. 6. The main body of secondary air flows outside the flame retention nozzle 50 and remains adjacent or close to the inner face of the heater tube 14, but some secondary air flows through the annular passage 58 between the burner tip 42 and the back plate 56. The plate 56 is itself supported by a number, in this case four webs 72, and these extend from plate 56 to a collar 74 which surrounds the tube 40. The webs 72 are cut away adjacent the tip 42 until they reach back to the collar 74, which is spaced rearward relative to the tip. In this way the annular passage 58 is not interrupted by the support webs 72.

The annular passage around the tip 42 may have a width from $\frac{1}{8}$ " to $\frac{1}{4}$ " in radial direction, on a nozzle or tip $1\frac{1}{4}$ " in diameter. The continuous annular passage has the advantage of avoiding turbulence and eddy currents inside the nozzle 50. Heretofore the gas or gas mixture would cause a vacuum at the back portion of the flame retention nozzle, but with our construction the vacuum is satisfied by the secondary air flowing smoothly through the annular passage. For best result the passage

should be a continuous annular passage, and it should be located immediately around the burner tip, and it should also be close to the burner tip in axial direction. Stop screw 76 (Fig. 3) locates ring 74, and the latter has screws 78 (Fig. 6) for mounting.

The continuous sleeve of air here provided by the uninterrupted annular passage 58 eliminates carbon formation and results in a better shape of flame and control of flame within the nozzle 50.

10 The cylindrical portion 50 of the flame retention nozzle is secured to the support or back plate 56 by means of a plurality of screws shown at 70 (Fig. 6), the heads of which are given enough length to act as the centering spacers previously referred to. The cylindrical part 50 of the flame retention nozzle preferably has a length approximating its diameter.

15 Referring now to Figs. 1, 4 and 5, the air supply body 44 receives an air supply pipe, as by means of a flange connection 80. The air deflecting vane 54 is carried by 20 a pin 82 having a control handle 84 secured to pin 82 outside the body 44. There is also a scale 86 to indicate the direction of adjustment of flame length, and it will be noted from inspection of Figs. 4 and 5 that maximum deflection is marked "Long" and that minimum deflection with the vane turned out of the way, as indicated in Figs. 25 4 and 5, is marked "Short." This is opposite to the conventional marking for furnace burners in which whirled air produces a shortened flame. It will be understood that if increased deflection reduces the air flow and thus causes smoke, the valve shown at 30 in Fig. 2 is opened enough to restore sufficient air. Indeed the adjustment of the gas valve 34 (Fig. 2) as well as the air valve 30 must be considered variable rather than constant, until a desired burner flame is attained. For example, movement of the sleeve 30 35 60 (Fig. 1) to the right to admit a greater supply of primary air inside the tube 40 helps reduce the gas supply, for the increased air pressure within the tube 40 opposes the incoming gas. Therefore adjustment of sleeve 60 toward the right will ordinarily be accompanied by greater opening of the gas supply valve 34 in order to maintain the desired rate of combustion of gas for whatever work the radiant heater tube or furnace is doing.

40 The secondary air flows through the annular passage 48 (Fig. 1) outside the tube 40 and then follows a helical path in the space between the tube 40 and the heater tube 14. The burner has considerable overall length and this affords time for the whirling air to move outward by centrifugal force so that it tends to hug the outer wall in its travel. We believe this slows and delays the admixture 45 50 of the secondary air with the fuel and primary air discharged from the burner tip 42 and thus makes it possible to greatly prolong the duration of the fuel consumption and to correspondingly elongate the flame. Similarly a decrease in primary air and an increase in secondary air 55 delays combustion and increases the flame length.

The secondary air is released far back of the ignition point (burner tip 42), and is released into a large chamber, that is, the space between tubes 40 and 14, and thus the secondary air can assume a smooth streamlined flow 60 and will be guided outward around the flame retention nozzle 50 with or without whirling of the secondary air, but the whirl helps delay combustion and thus additionally lengthens the flame. Either way there is a minimum of eddy current and turbulence.

65 Of course, when the sleeve 60 is moved toward the right, thereby constricting the annular passage 48, the effect of the deflecting vane to whirl the secondary air is reduced, but this is at a time when the burner is being adjusted for a short flame. Therefore both adjustments 70 work in the same direction.

With the present burner a very wide range of adjustment of flame length may be obtained. There is no difficulty in reducing the flame down to a few feet in length when the burner is to be used in a very short radiant tube, and, on the other hand, in elongating the flame until it

projects from and is readily visible well beyond the discharge end of a radiant tube twenty feet or more in length.

Reverting now to Fig. 1, the gas body 90 has a cylindrical forward end 92 which is received in a mating opening 94 in the air body 44. These parts are secured together as by means of a radial screw 96 (Fig. 4) received in a groove 97 (Fig. 1). The body 90 is rotatable relative to the body 44 so that the gas and air pipes can come into the burner in any desired direction. For example, the gas may come from beneath and the air from above. The tube 40 is secured to the gas body 90 by a press fit aided by a transverse drive pin (not shown). The burner tip 42 is secured to the tube 40 by a press fit aided by a transverse drive pin (not shown). The gas pipe is connected to the gas body 90, as by means of a flange connection 98. In the specific case here shown the flange connection is for a $\frac{3}{4}$ " gas pipe, while the flange connection 80 is for a $1\frac{1}{2}$ " air pipe, for a burner used in a 4" or 5" radiant tube. This is mentioned by way of example, and not as a limitation of the invention.

As is already known in the art, thin orifice plates may be inserted between the flange connections and the bodies, as a measure of regulation of the gas and air supplies to help meet conditions at any particular installation, for gas may be available at one particular pressure, and air may be available at a very different pressure, because of equipment already installed and functioning at the plant for other purposes. It is also a safety feature against overloading the burner and the radiant tube which is made of expensive alloy, and should not be burned out.

The burner may be ignited in conventional fashion, by means of an electrode to which high tension electric current is supplied. Specifically, there is a terminal 38, having an insulation body 100 somewhat resembling a spark plug, and similarly screwed through a threaded opening. The conductor of the terminal is formed into a loop or eye at 102 where it receives a horizontal rod 104 which in turn passes through a cylindrical insulator 106 held in position by a clamp plate 108 and screw 110. The insulator may pass through the back plate 56 of the flame retention nozzle 50, and terminates in an inwardly turned electrode 112. The circuit is completed by a "ground" connection to the body of the burner.

The burner may be provided with an observation port, and this is shown at 114 in Figs. 1, 4, and 5. It includes a transparent window held in place by the hollow screw plug shown at 114. The small screw plugs 116 and 117 shown in Fig. 1 are for convenience in connecting a pressure gauge or manometer to the burner for test purposes.

The air supply body 44 includes a plate 120, in this case having a generally square shape which is best shown in Figs. 1, 4 and 5. This has holes at the corners to receive screws or bolts to mount the burner in position. For this purpose the radiant tube 14 terminates at its outer end in a plate 122 which may be welded to the end of the radiant tube, as shown at 124. The plate 122 is provided with holes aligned with the corner holes 126 of the burner, and thus the burner is mounted in place by securing plate 120 to plate 122.

One of the manufacturing advantages of the arrangement here disclosed is that the overall length of the burner may be varied while using standard parts at each end of the burner. It is only necessary to change the length of the tube 40 and the electrode rod 104. In practical application this is an important advantage because different installations require different overall length of burner. In all cases it is desirable that the flame retention nozzle 50 reach or nearly reach the inner face of the masonry or firebrick wall, as shown at 16 in Fig. 1 of the drawing. This is so because the heater tube 14 should not be exposed on the inside to flame and heat at a point where there would be no medium for effective dissipation of heat from the outside. Thus the thickness of the masonry wall 16 will itself be a factor in determining the minimum length of burner. Other factors may enter into particular installations, such as 75

the room required for making pipe connections outside the furnace, or, in other words, the projection of the radiant tube 14 from the furnace, as shown in Fig. 2, and the nature of the flue connection at the discharge end of the heater tubes when the tubes are of the U or W type.

It is believed that the construction and operation of our improved gas burner for tube firing, as well as the advantages thereof, will be apparent from the foregoing detailed description. The burner is made in several sizes corresponding to large changes in diameter of the heater tube. Each burner size may be used with several different sizes of radiant tube, but a large change in tube size is accommodated by a change in burner size. The burner may be supplied in different lengths, depending on the requirements of the purchaser, and a change in length is readily accommodated at the factory, as previously explained.

The burner produces a flame the length of which is adjustable over a very wide range. In most practical cases the burner flame may be adjusted to be as long as the heater tube in which it is used. The flame length is adjusted by varying the ratio of primary air to secondary air by means of a convenient outside adjustment at 52, and also by varying the whirl of the air by means of the convenient outside adjustment 84.

The burner ignites easily and quietly. The formation of carbon is eliminated. The great length of the burner affords ample opportunity for the secondary air to move outward, aided by centrifugal force, before reaching the combustion zone.

It will be understood that while we have shown and described our invention in a preferred form, changes may be made in the structure shown, without departing from the scope of the invention, as sought to be defined in the following claims. In the claims the reference to external adjustment means is not intended to exclude a control which is covered or concealed by a cap or plate to prevent unauthorized changes in adjustment. It refers preferably to a means which can be varied while the burner is in operation, so that the results of the adjustment may be watched.

We claim:

1. In combination, a heater tube which is very long compared to its diameter and which is non-insulated and adapted to be used as a heat exchanger for providing intentional transfer of heat through the tube wall, and a burner which is long compared to its diameter and which has forward and rear portions connected by a primary tube, most of said burner being smaller in diameter than the heater tube and being inserted longitudinally of the heater tube into one end of the heater tube, said heater tube terminating in an outlet at its other end, said primary tube terminating at its inner end in a burner tip and having its rear end portion projecting from the heater tube, an air supply body surrounding the rear end portion of the primary tube and connected to a source of air to supply secondary air to flow outside the primary tube in the space between the primary tube and the heater tube, a gas connection to the primary tube, ports in said primary tube within the air supply body to supply air to the primary tube for mixture with the gas in the primary tube, means in said air supply body to whirl the combustion air and cause it to assume a helical path as it moves forward around the outside of the primary tube, said primary tube being designed to afford a straight flow therethrough, a sleeve valve slidable over the ports in said primary tube, external adjustment means for shifting said valve to vary the gas to air ratio in the primary tube, the forward end of said burner being designed to direct the flow thereof in axially forward direction, the combination serving to delay admixture of secondary air with the fuel in order to prolong the flame for more uniform heating of the heater tube along its length.
2. In combination, a heater tube which is very long

compared to its diameter and which is non-insulated and adapted to be used as a heat exchanger for providing intentional transfer of heat through the tube wall, and a burner which is long compared to its diameter and which has forward and rear portions connected by a primary tube, most of said burner being smaller in diameter than the heater tube and being inserted longitudinally of the heater tube into one end of the heater tube, said heater tube terminating in an outlet at its other end, said primary tube terminating at its inner end in a burner tip and having its rear end portion projecting from the heater tube, an air supply body surrounding the rear end portion of the primary tube and connected to a source of air to supply secondary air to flow outside the primary tube in the space between the primary tube and the heater tube, a gas connection to the primary tube, ports in said primary tube within the air supply body to supply air to the primary tube for mixture with the gas in the primary tube, flame retention means at the end of the primary tube, said means having a diameter larger than the primary tube and smaller than the heater tube, means in said air supply body to whirl the combustion air and cause it to assume a helical path as it moves forward around the outside of the primary tube, said primary tube being designed to afford a straight flow therethrough, a sleeve valve slidable over the ports in said primary tube, external adjustment means for shifting said valve to vary the gas to air ratio in the primary tube, the forward end of said burner being designed to direct the flow thereof in axially forward direction, the combination serving to delay admixture of secondary air with the fuel in order to prolong the flame for more uniform heating of the heater tube along its length.

3. In combination, a heater tube which is very long compared to its diameter and which is non-insulated and adapted to be used as a heat exchanger for providing intentional transfer of heat through the tube wall, and a burner which is long compared to its diameter and which has forward and rear portions connected by a primary tube, most of said burner being smaller in diameter than the heater tube and being inserted longitudinally of the heater tube into one end of the heater tube, said heater tube terminating in an outlet at its other end, said primary tube terminating at its inner end in a burner tip and having its rear end portion projecting from the heater tube, an air supply body surrounding the rear end portion of the primary tube and connected to a source of air to supply secondary air to flow outside the primary tube in the space between the primary tube and the heater tube, said air supply body having an annular passage to said space, a gas connection to the primary tube, ports in said primary tube within the air supply body to supply air to the primary tube for mixture with the gas in the primary tube, flame retention means at the end of the primary tube, said means having a diameter larger than the primary tube and smaller than the heater tube, means in said air supply body to whirl the combustion air and cause it to assume a helical path as it moves forward around the outside of the primary tube, said primary tube being designed to afford a straight flow therethrough, a sleeve valve slidable over the ports in said primary tube, external adjustment means for shifting said valve to vary the gas to air ratio in the primary tube, means to vary the size of the annular passage between the air supply body and the heater tube, the forward end of said burner being designed to direct the flow thereof in axially forward direction, the combination serving to delay admixture of secondary air with the fuel in order to prolong the flame for more uniform heating of the heater tube along its length.

4. In combination, a heater tube which is very long compared to its diameter and which is non-insulated and adapted to be used as a heat exchanger for providing intentional transfer of heat through the tube wall, and a

burner which is long compared to its diameter and which has forward and rear portions connected by a primary tube, most of said burner being smaller in diameter than the heater tube and being inserted longitudinally of the heater tube into one end of the heater tube, said heater tube terminating in an outlet at its other end, said primary tube terminating at its inner end in a burner tip and having its rear end portion projecting from the heater tube, an air supply body surrounding the rear end portion of the primary tube and connected to a source of air to supply secondary air to flow outside the primary tube in the space between the primary tube and the heater tube, said air supply body having an annular passage to said space, a gas connection to the primary tube, ports in said primary tube within the air supply body to supply air to the primary tube for mixture with the gas in the primary tube, flame retention means at the end of the primary tube, said means having a diameter larger than the primary tube and smaller than the heater tube, means in said air supply body to whirl the combustion air and cause it to assume a helical path as it moves forward around the outside of the primary tube, said primary tube being designed to afford a straight flow therethrough, a sleeve valve slidable over the ports in said primary tube, external adjustment means for shifting said valve to vary the gas to air ratio in the primary tube, means to vary the size of the annular passage between the air supply body and the heater tube, said means and sleeve being connected to simultaneously and oppositely vary the size of the primary and secondary air passages, the forward end of said burner being designed to direct the flow thereof in axially forward direction, the combination serving to delay admixture of secondary air with the fuel in order to prolong the flame for more uniform heating of the heater tube along its length.

5. In combination, a heater tube which is very long compared to its diameter and which is non-insulated and adapted to be used as a heat exchanger for providing intentional transfer of heat through the tube wall, and a burner which is long compared to its diameter and which has forward and rear portions connected by a primary tube, most of said burner being smaller in diameter than the heater tube and being inserted longitudinally of the heater tube into one end of the heater tube, said heater tube terminating in an outlet at its other end, said primary tube terminating at its inner end in a burner tip and having its rear end portion projecting from the heater tube, an air supply body surrounding the rear end portion of the primary tube and connected to a source of air to supply secondary air to flow outside the primary tube in the space between the primary tube and the heater tube, said air supply body having an annular passage to said space, a gas connection to the primary tube, ports in said primary tube within the air supply body to supply air to the primary tube for mixture with the gas in the primary tube, flame retention means at the end of the primary tube, said means having a diameter larger than the primary tube and smaller than the heater tube, means in said air supply body to whirl the combustion air and cause it to assume a helical path as it moves forward around the outside of the primary tube, said primary tube being designed to afford a straight flow therethrough, a sleeve valve slidable over the ports in said primary tube, external adjustment means for shifting said valve to vary the gas to air ratio in the primary tube, means to vary the size of the annular passage between the air supply body and the heater tube, said means and sleeve being connected to simultaneously and oppositely vary the size of the primary and secondary air passages, the forward end of said burner being designed to direct the flow thereof in axially forward direction, the combination serving to delay admixture of secondary air with the fuel in order to prolong the flame for more uniform heating of the heater tube along its length.

6. In combination, a heater tube which is very long compared to its diameter and which is non-insulated and adapted to be used as a heat exchanger for providing intentional transfer of heat through the tube wall, and a burner which is long compared to its diameter and which has forward and rear portions connected by a primary tube, most of said burner being smaller in diameter

ameter than the heater tube and being inserted longitudinally of the heater tube into one end of the heater tube, said heater tube terminating in an outlet at its other end, said primary tube terminating at its inner end in a burner tip and having its rear end portion projecting from the heater tube, an air supply body surrounding the rear end portion of the primary tube and connected to a source of air to supply secondary air to flow outside the primary tube in the space between the primary tube and the heater tube, said air supply body having an annular passage to said space, a gas connection to the primary tube, ports in said primary tube within the air supply body to supply air to the primary tube for mixture with the gas in the primary tube, flame retention means at the end of the primary tube, said means having a diameter larger than the primary tube and smaller than the heater tube, a sleeve valve slidable over the ports in said primary tube to vary the size of the air passage, external adjustment means for shifting said valve to vary the gas to air ratio in the primary tube, means to vary the size of the annular passage between the air supply body and the heater tube, said means and sleeve being connected to simultaneously and oppositely vary the size of the primary and secondary air passages, the forward end of said burner being designed to direct the flow therat in axially forward direction, the combination serving to delay admixture of secondary air with the fuel in order to prolong the flame for more uniform heating of the heater tube along its length.

7. The combination defined in claim 1, in which the means to whirl the secondary air is an angularly adjustable deflecting vane in the air supply body together with external means for adjusting the position of the vane.

8. The combination defined in claim 2, in which the means to whirl the secondary air is an angularly adjustable deflecting vane in the air supply body together with external means for adjusting the position of the vane.

9. The combination defined in claim 3, in which the means to whirl the secondary air is an angularly adjustable deflecting vane in the air supply body together with external means for adjusting the position of the vane.

10. The combination defined in claim 4, in which the means to whirl the secondary air is an angularly deflecting vane in the air supply body together with external means for adjusting the position of the vane.

11. The combination defined in claim 2, in which the flame retention means is a nozzle having a cylindrical wall and an annular back plate, said back plate surrounding the primary tube but being radially spaced therefrom to provide an annular passage around the burner tip for forward flow of a portion of the secondary air.

12. The combination defined in claim 4, in which the flame retention means is a nozzle having a cylindrical wall and an annular back plate, said back plate surrounding the primary tube but being radially spaced therefrom to provide an annular passage around the burner tip for forward flow of a portion of the secondary air.

13. The combination defined in claim 6, in which the flame retention means is a nozzle having a cylindrical wall and an annular back plate, said back plate surrounding the primary tube but being radially spaced therefrom to provide an annular passage around the burner tip for forward flow of a portion of the secondary air.

14. The combination defined in claim 3, in which the slidable sleeve valve around the primary tube has a rear portion axially movable over the air ports, and in which said means to vary the size of the annular passage comprises a forward conically-surfaced portion of said valve movable to variably obstruct the annular passage from the air supply body to the heater tube, whereby axial movement of said sleeve valve simultaneously and oppositely varies the size of the primary and secondary air supply openings.

15. The combination defined in claim 4, in which the slidable sleeve valve around the primary tube has a rear

portion axially movable over the air ports, and in which said means to vary the size of the annular passage comprises a forward conically-surfaced portion of said valve movable to variably obstruct the annular passage from the air supply body to the heater tube, whereby axial movement of said sleeve valve simultaneously and oppositely varies the size of the primary and secondary air supply openings.

16. The combination defined in claim 15, in which the slidable sleeve valve around the primary tube has a rear portion axially movable over the air ports, and in which said means to vary the size of the annular passage comprises a forward conically-surfaced portion of said valve movable to variably obstruct the annular passage from the air supply body to the heater tube, whereby axial movement of said sleeve valve simultaneously and oppositely varies the size of the primary and secondary air supply openings.

17. The combination defined in claim 16, in which the slidable sleeve valve around the primary tube has a rear portion axially movable over the air ports, and in which said means to vary the size of the annular passage comprises a forward conically-surfaced portion of said valve movable to variably obstruct the annular passage from the air supply body to the heater tube, whereby axial movement of said sleeve valve simultaneously and oppositely varies the size of the primary and secondary air supply openings.

18. In combination, a heater tube which is very long compared to its diameter and which is non-insulated and adapted to be used as a heat exchanger for providing intentional transfer of heat through the tube wall, and a burner which is long compared to its diameter and which has forward and rear portions connected by a primary tube, most of said burner being smaller in diameter than the heater tube and being inserted longitudinally of the heater tube into one end of the heater tube, said heater tube terminating in an outlet at its other end, said primary tube terminating at its inner end in a burner tip and having its rear end portion projecting from the heater tube, an air supply body surrounding the rear end portion of the primary tube and connected to a source of air to supply secondary air to flow outside the primary tube in the space between the primary tube and the heater tube, said air supply body having an annular passage to said space, a gas connection to the primary tube, ports in said primary tube within the air supply body to supply air to the primary tube for mixture with the gas in the primary tube, flame retention means at the end of the primary tube, said means having a diameter larger than the primary tube and smaller than the heater tube, means in said air supply body to whirl the combustion air and cause it to assume a helical path as it moves forward around the outside of the primary tube, said primary tube being designed to afford a straight flow therethrough, means to vary the size of the annular passage between the air supply body and the heater tube, the forward end of said burner being designed to direct the flow therat in axially forward direction, the combination serving to delay admixture of secondary air with the fuel in order to prolong the flame for more uniform heating of the heater tube along its length.
